(57) **CLAIM**

The ornamental design for a spring fixed telescopic device, as shown and described.

DESCRIPTION

FIG. 1 is a front, right and top perspective view of a spring fixed telescopic device, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an exploded view thereof.

FIG. 10 is an environmental front, right and top perspective view of the spring fixed telescopic device in a first usable state; and,

FIG. 11 is an environmental front, right and top perspective view of the spring fixed telescopic device in a second usable state.

The broken line showing in FIGS. 10 and 11 illustrates the environment of the claimed design and forms no part thereof. The remaining broken lines in the drawings depict portions of the Connector that form no part of the claimed design.
